DESIGN FOR A PENCIL

Beatrice B. Blake, Los Angeles, Calif., assignor of one-half to Eleanor L. Gernert

Application September 3, 1938, Serial No. 79,740

Term of patent 14 years

To all whom it may concern:

Be it known that I, Beatrice B. Blake, a citizen of the United States of America, residing at Los Angeles, in the county of Los Angeles and State of California, have invented a new, original, and ornamental Design for a Pencil, of which the following is a specification, reference being had to the accompanying drawing, forming part thereof.

Fig. 1 is a side perspective view of a pencil showing my new design; and

Fig. 2 is a side perspective view of the opposite side of the pencil as is shown in Fig. 1.

I claim:

The ornamental design for a pencil, as shown.

BEATRICE B. BLAKE.
